UNITED STATES PATENT OFFICE

139,330

DESIGN FOR A BEDSTEAD OR SIMILAR ARTICLE

Joseph Russell, Ravenna, Mich.

Application May 24, 1944, Serial No. 113,744

Term of patent 14 years

(Cl. D5—4)

To all whom it may concern:

Be it known that I, Joseph Russell, a citizen of the United States, residing at Ravenna, in the county of Muskegon and State of Michigan, have invented a new, original, and ornamental Design for a Bedstead or Similar Article, of which the following is a specification, reference being had to the accompanying drawing, forming a part thereof.

The other side of the head board and foot board panels are the same as that shown in Figures 2 and 3.

I claim:

The ornamental design for a bedstead or similar article, as shown and described.
